UNITED STATES PATENT OFFICE

TALMA T. GREENWOOD, OF EAST TEMPLETON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

CIRCUIT INTERRUPTER

Application filed June 29, 1929. Serial No. 374,838.

This invention relates to alternating current electric switches and circuit interrupters and particularly to a method and means for interrupting the alternating current circuit-interrupting arc that is drawn between the separable contact members of the switch. The alternating current arc goes out periodically at the end of each half cycle, when the current passes through zero, and usually is re-established at the beginning of the succeeding half cycle when the potential across the arc terminals becomes sufficiently great to overcome the resistance of the arc zone.

One of the objects of the present invention is a method and apparatus for removing the conducting ions from the arc zone during the time that the arc is out while the current is passing through the zero point of the wave and for delaying for a determined time the re-establishment of voltage across the arc terminals or for increasing the period of time that the potential across the arc terminals is substantially zero, or is insufficient to pass an arc current through the arc zone, so that the ion-removing means can have an increased period of time during which to act, thus to be more effective in building up the dielectric strength of the arc zone and thereby preventing the re-establishment of the arc.

In carrying out this object of the invention, it is a specific object to impress a potential on the circuit to be interrupted, which impressed potential preferably is less than the maximum potential of the circuit and has a greater frequency as, for instance, triple the frequency, so that it modifies the potential of the circuit to be interrupted and reduces said potential practically to zero for a determined time on both sides of the normal zero point of the potential wave. The method thus increases the time at which the arc terminals are substantially free from potential and thus gives the ion-removing device an increased period of time during which to act with greatest effectiveness.

A further object is generally to improve upon circuit interrupting apparatus and methods.

Fig. 1 is a diagram illustrating the separable contact members of an electric switch

and the circuit connections therefor arranged in accordance with the present invention.

Fig. 2 is a diagram illustrating the type of arc potential wave and the increased period of zero arc potential obtained with the invention.

The alternating current switch or circuit interrupter here shown includes the stationary contact member 10 and the movable contact member 12 which are in series in the alternating current circuit 14 and are normally in engagement to complete said circuit and are adapted to be separated to interrupt the circuit. Upon separation of the contact members, an arc is drawn between them, which arc of necessity goes out and, in the ordinary switch, is re-established at successive half cycles of the current. Means are provided herein to remove the conducting ions from the arc zone between the separated contact members whereby to increase the dielectric strength of the medium in the arc zone to such a point that the dielectric strength is greater than the potential that is impressed on the arcing members, whereby the arc cannot be re-established.

Said means is most effective at the time that the arc is momentarily extinguished when the arc current passes through the zero point of the wave. Said means, as here shown, includes an electrostatic field producing means as a ring 16 which ring surrounds the arc and the field of the ring is effective throughout the arc zone and the space occupied by the arcing surfaces of the contact members. Said ring is energized by a suitable source, herein diagrammatically illustrated as the battery 18, which source impresses upon the ring a potential sufficiently great to remove the ions from the arc zone and prevent them passing between the contact members in sufficiently large numbers to render the arc zone conducting to the normal arc potential. Since the potential across the contact members, or the arc terminals, increases relatively rapidly when building up from the zero point of the potential wave, the time available for the ion-removing means to act upon the arc zone before the re-establishment of the arc is

relatively small. In accordance with this invention, means are provided to delay the building up of potential at the normal zero point of the potential wave whereby to increase the time that the ion-removing means is free to act unimpeded on the arc zone. Said means includes an alternating current generator 20 which energizes the primary winding 22 of a transformer, the secondary winding of which is connected and, as here shown, is in series with the power circuit 14. The generator 20 thus impresses upon the power circuit an alternating potential which is a function of the potential and frequency of the generator. Preferably, the frequency of the generator 20 is higher than the frequency of the potential in the power circuit 14, preferably by some multiple such that both potentials pass through their zero points at the same time. The generator 20 may, for instance, set up a potential in the power circuit 14 that is triple the frequency of the normal potential of said power circuit. The impressed potential acts upon the circuit potential to flatten the wave at the zero point as is indicated in Fig. 2. In this figure, 26 represents the potential wave of the power circuit 14 while 28 represents the high frequency impressed potential. The resultant of the two potential waves gives the potential wave 30 which is the one impressed across the arc terminals.

It will be noted that this resultant wave is substantially zero for a number of degrees on both sides of the zero point of the normal potential wave 26 as indicated at 32. If both the potential waves 26 and 28 are sine waves, the resultant potential wave 30 may not be reduced completely to zero in the region of the normal zero point but at least the resultant potential will be so low that it is insufficient to re-establish and support a persistent arc.

The resultant potential in the region of the zero point may be reduced more completely to zero if the potential waves 26 and 28 are made complements of each other at this point as by having the potential wave 28, in an obvious manner, follow a suitable curve that is something other than a sine curve. Thus, by accelerating the decay of the potential wave on one side and delaying the building up of potential on the other side of the normal potential zero, a greatly increased time period is provided during which the arc potential is zero and the ion-removing means 16 is free to act unimpededly upon the arc zone, thus to enhance its effectiveness.

60 The method and apparatus herein disclosed for removing ions from the zone of the arc is described and claimed in my co-pending application Serial No. 152,048, filed December 1, 1926.

65 I claim:

1. An alternating current circuit interrupter having separable contact members between which a circuit interrupting arc is established upon separation of said contact members, means to remove ions from the arc zone between said separated contact members, and means to delay the re-establishment of the arc potential between said separated contact members during the reversal of arc polarity including means to modify the character of the wave of the arc potential and to maintain it substantially at zero for a definite period of time on both sides of the normal zero point of its wave. 70

2. An alternating current circuit interrupter having separable contact members between which a circuit interrupting arc is established upon separation of said contact members, means to remove ions from the arc zone between said separated contact members, and means to maintain the arc potential substantially at zero for a definite period of time on both sides of the normal zero point of its wave. 80

3. An alternating current circuit interrupter having separable contact members between which a circuit interrupting arc is established upon separation of said contact members, means to remove ions from the arc zone between said separated contact members, and means to supply the arc with current at an alternating potential which has substantially zero value for definite periods of time. 90

4. An alternating current circuit interrupter having separable contact members between which a circuit interrupting arc is established upon separation of said contact members, means acting when the arc current is zero to remove ions from the arc zone between said separated contact members, and means to delay the re-establishment of the arc potential between said separated contact members during the reversal of arc polarity including means to impress an alternating potential upon the arc potential, said alternating potential having a value and being at a frequency which differs from that of the frequency of the arc potential by such values as to maintain the arc potential substantially at zero for definite periods of time. 100

5. An alternating current circuit interrupting apparatus having separated arc terminals between which an alternating current arc is supported, means acting when the arc current is zero to remove conducting ions from the arc zone between said terminals, and means to supply said terminals with an alternating potential which is maintained substantially at zero for definite periods of time. 110

6. An alternating current circuit interrupting apparatus having separated arc terminals between which an alternating cur- 120

115

125

130

rent arc is supported, means to remove conducting ions from the arc zone between said terminals, and means to supply said terminals with an alternating potential which is 5 at a value that is insufficient to pass an arc current between said terminals for predetermined periods of time.

7. The method of interrupting an alternating current electric arc which consists in 10 supplying the arc with an alternating potential which is substantially at zero for predetermined periods of time, and removing ions from the arc zone during such periods.

8. The method of extinguishing an alternating current arc which consists in supplying the arc with a potential that for definite periods of time has a value lower than that necessary to initiate the arc, and removing ions from the arc zone during such 20 periods.

9. The method of interrupting an alternating current electric arc which consists in supplying the arc with an alternating potential, modifying said potential by an impressed alternating potential of different frequency such as to provide a resultant arc potential that is substantially at zero for predetermined periods of time, and removing ions from the arc zone during such periods.

30 In testimony whereof, I have signed my name to this specification.
